UNITED STATES PATENT OFFICE.

WILHELM BACHNER, OF STUTTGART, GERMANY.

REFRIGERATING ICE-CHAMBER.

SPECIFICATION forming part of Letters Patent No. 634,791, dated October 10, 1899.

Application filed August 16, 1898. Serial No. 688,670. (No model.)

To all whom it may concern:

Be it known that I, WILHELM BACHNER, a citizen of the Empire of Germany, residing at Stuttgart, in the Kingdom of Würtemberg, Germany, have invented certain new and useful Improvements in Refrigerators; and I do hereby declare the following to be a full, clear, and exact description of the invention, such as will enable others skilled in the art to which it appertains to make and use the same.

The ice-chests or refrigerating-chambers hitherto employed have the drawbacks in many instances that owing to the want of a circulation of air water is deposited on the food products intended to be preserved, which is particularly deleterious for meat, (especially cooked meat,) sausage, butter, and the like, and considerably shortens the duration of their preservation. Furthermore, the ice-chambers are mainly so arranged that on the opening of the door or doors a large part of the cold air escapes, as the ice-tank is not closed while the chamber is being opened and the doors usually extend to the bottom. Further, no arrangement is even made for the automatic discharge of the ice-water from the chest and at the same time preventing the admission of the outer air. All these drawbacks are entirely removed by my improved ice-chest, which has been tested for a long time.

In the accompanying drawings, Figure 1 is a vertical longitudinal sectional view of my improved refrigerator, and Fig. 2 is a horizontal sectional view thereof on the line *x x*. Fig. 3 is a vertical transverse sectional view. Figs. 4, 5, and 6 are detail views of the separate doors employed for preventing escape of cold air when the outer or main doors of the refrigerator are opened. Fig. 7 is a front elevation; and Fig. 8 is a similar view to Fig. 2, showing the position assumed by the inner working parts when the outer doors are opened.

An ice-holder *C*, resting on supports *G*, is inserted in the center of the internal-chamber of the ice-chamber *A* and is widened above and closed by means of a removable cover *B* by an iron frame *b* on the under part of the latter, which frame runs all around and is of *J*-shaped section, resting on and forming a tight joint, with a frame *c* of similar

shape and *L*-shaped section on the upper part of the ice-chest. The lower part of the ice-holder *C* ends in a hopper-shaped extension *C'*, the outlet of which is provided with a flap or valve *J*, which is automatically closed and opened on the doors *T* being opened and closed, respectively. This is effected by means of angle-pieces *t*, attached to the doors, on which forked pieces *p* are pivotally mounted, which are connected with bell-crank *M* by links *n*. The said bell-crank *M* are connected with the valve *J* by means of cords *s* carried over rollers *r*, so that the opening or closing of either one of the two doors is sufficient to automatically close or open the valve *J*. The said extension *C'*, at its lower part, is bent or turned rearwardly, so as to permit of the opening of the inwardly-swinging inner doors *T'*, hereinafter described. A grating *H*, on which the ice rests, is arranged as usual in the ice-container, so that only ice-water and no ice can come into the hopper *C'*. The hopper *C'* also forms a cold-air-storage chamber, as hereinafter more fully understood, so that on the closing of the doors the air accumulated therein descends with pressure into the cool chamber, and thereby produces an increased circulation of air therein. Openings *c'* are provided in the upper part of the ice-holder, and in order to produce a better circulation of the air the two shorter side walls *a* of the chamber are made inclined like a roof, so that the rising warmer air is directed to the openings *c'* in the ice-holder *C*, while the cold air descends in the latter and, so long as the valve *J* is not closed, passes into the chest from the lower orifice of the hopper *C'*. A constant automatic circulation of air thus takes place in the direction indicated by the arrows, which, however, at once ceases through the closing of the valve *J* on the opening of the doors, so that the cold air remains accumulated in the hopper until the doors are again closed.

In order that the circulation of air in the interior of the ice-holder shall not be impeded—for instance, by the caking of the ice—a tube *F*, having apertures or slots, is arranged inside the holder and stands on the grating *H*.

A vessel *D* for catching the water is arranged against the rear wall of the refriger-

ator under the hopper C', which vessel is divided into two compartments by means of a partition D' and from which the ice-water is conveyed to the outside by means of a siphon-pipe E. The pipe E has outside an oblique closing flap or valve e, which is opened automatically by the water itself running away, while the partition D' prevents the outside air penetrating into the ice-holder.

In order to cause the warmer air to be expelled from the ice-holder on the closing of the doors, which causes a compression of the air in the said holder, while retaining the cold air in the latter, the following arrangement is adopted: The cover B of the container has an opening on which a short tube b' is mounted, the opening of which is closed by an india-rubber ball or valve k. The latter is covered by a cap b², having small openings in the top, which cap limits the movement of the ball or valve k, but allows air to escape from the ice-chest on the opening of the said valve k. When the doors T are closed, the air in the holder is compressed, and the warmer air at the top escapes through a momentary lifting of the ball or valve k, Fig. 1. The doors T are also so arranged that they do not extend to the bottom of the inner chamber, but a considerable distance intervenes between the lower edge of the doors and the floor. Further, on the inner side of the doors and within the chamber at the bottom separate doors T', Figs. 4, 5, and 6, are arranged, which open inwardly. By so arranging the inner doors they may be thrown open and kept so permanently whenever the refrigerating-chamber is to be completely filled with articles or when very large bulks are placed within such chamber, so that less difficulty will be had in removing the articles than if the said doors were allowed to remain closed. In other instances the said inner doors are closed to prevent as much as possible the escape of cold air whenever the outer doors are opened. These inner doors extend some distance above the lower edge of the outer doors, as shown in Fig. 3. On the opening of the doors the cold air, lying at the deepest part, remains in the ice-holder, Fig. 3. The doors T are also connected with weights W, which on the fastening-bolt of the doors being drawn back the latter open automatically, and simultaneously the valve J also automatically closes. These weights have for their object to bring the doors fully open; but when they are not required to be fully open they must always be entirely closed, so that self-evidently a considerable saving of refrigerating material is effected.

With a very moderate consumption of ice such an excellent air-circulation is created in the refrigerating-chamber by the arrangement hereinbefore described that actually no deposit of water on the food products to be cooled takes place, the latter remaining quite

dry and may be preserved a much longer time. In small refrigerating-chambers the ice-holder may of course be placed at the side instead of the center of the same, while for larger sizes several ice-holders may be advantageously provided in the chamber.

Having now particularly described and ascertained the nature of my said invention and in what manner the same is to be performed, I declare that what I claim is—

1. The combination, in a refrigerator, of a cooling-chamber provided with an outer door, and an inner door operating, when shut, to close the lower part of the opening fully covered by said outer door, whereby escape of cold air from the lower part of the cooling-chamber is prevented during access to said chamber.

2. The combination, in a refrigerator, of a cooling-chamber provided with outer doors, and inner doors operating, when shut, to close the lower part of the opening fully covered by said outer doors, whereby escape of cold air from the lower part of the cooling-chamber is prevented during access to said chamber.

3. The combination, in a refrigerator, of a cooling-chamber provided with an outer door, an inner door operating, when shut, to close the lower part of the opening fully covered by said outer door, whereby escape of cold air from the lower part of the cooling-chamber is prevented during access to said chamber, an ice-holder extending into the chamber, and a drip-pan beneath said holder.

4. The combination, in a refrigerator, of a cooling-chamber provided with outer doors, inner doors operating, when shut, to close the lower part of the opening fully covered by said outer doors, for the purpose described, an ice-holder supported in the top of the chamber, and extending to a point below the upper edge of the door-opening, an air-storage chamber at the bottom of said ice-holder, and means operated by the opening of the outer doors for closing said storage-chamber.

5. The combination, in a refrigerator, of a cooling-chamber provided with outer doors, inner doors operating, when shut, to close the lower part of the opening fully covered by said outer doors, an ice-holder supported in the top of the chamber, and extending to a point below the upper edge of the door-opening, an air-storage chamber at the bottom of said ice-holder, and means operated by the opening of the outer doors for closing said storage-chamber.

6. The combination, in a refrigerator, of a cooling-chamber provided with outer doors, inner doors operating, when shut, to close the lower part of the opening fully covered by said outer doors for the purpose described, an ice-holder supported in the top of the cooling-chamber, and provided in its top with a valve opening to the atmosphere, and an air-storage chamber at the lower end of the ice-holder, the same provided with a valve for opening and closing said storage-chamber,

said first-named valve operating to release the warm air produced in the ice-holder, by the closing of the said outer doors.

7. The combination, in a refrigerator, of a cooling-chamber provided with outer doors, inner doors operating, when shut, to close the lower part of the opening fully covered by said outer doors for the purpose described, an ice-holder having openings for the circulation of air from the cooling-chamber, and provided in its top with a valve opening to the

atmosphere, an air-storage chamber at the lower end of said ice-holder, a valve for said storage-chamber, and means for closing and opening said latter valve on the opening and closing of said outer doors. 15

In testimony whereof I affix my signature in presence of two witnesses.

WILHELM BACHNER.
